FURNACE REGULATOR

Charles A. Harpman, Youngstown, Ohio

Application March 16, 1939, Serial No. 262,137

4 Claims. (Cl. 236—10)

This invention relates to a furnace regulator. The principal object of this invention is the provision of a thermostatic control for a warm air furnace that is simple in construction, efficient in operation and capable of easy installation.

A further object of this invention is the provision of a thermostatic control for a warm air furnace formed of a plurality of stamped parts, thus making it inexpensive to manufacture.

A further object of this invention is the provision of a thermostatic control for a warm air furnace that is provided with spring tension means for holding the various movable parts in operating position so that any slack in the jointed parts will be taken up.

A still further object of this invention is the provision of a thermostatic control for warm air furnaces incorporating the use of a novel leverage principle whereby the control arm of the device is actuated with increasing quickness as it approaches either end of its range of operation, so that when the temperature of the furnace remains at or near a constant level, the control arm of the thermostatic control will move but slightly and when the furnace heats or cools rapidly the novel leverage principle provided serves to rapidly increase the motion of the control thus in effect opening or closing the draft much faster than would ordinarily be the case.

The furnace regulator shown and described herein has been designed to overcome one of the major objections to this general type of thermostatic control apparatus, wherein a bi-metallic expanding and contracting motion is utilized to control the draft and checks of a warm air furnace. In the furnace regulators of this type heretofore known to the art many and various principles of leverage have been employed with, however, the uniform result that the movement of the draft and check actuating arm of the regulator is always in direct relation and degree to the expansion and contraction of the bi-metallic unit incorporated as a part of the regulator. It is, therefore, the purpose of this invention to provide means in a bi-metallic expansion and contraction actuated regulator that will speed up the normal motion of such a device, thus when the furnace cools the device shown and described herein will respond with the normal or average movement degree but will, upon reaching a pre-determined point of normal movement, be actuated thru the novel leverage principles employed therein to rapidly move and thus effectively open the draft of the furnace and

close the check thereof at a much faster rate than would ordinarily be the case.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawing, wherein:

Figure 1 is a side elevation of the device with parts broken away. Dotted lines on Figure 1 showing the relative position of the various parts thereof when the same have been actuated.

Figure 2 is a top plan view of a portion of Figure 1 taken on lines 2—2 thereof.

Figure 3 is an enlarged detail view partly in cross section of one of the actuating arm mounting brackets shown in Figure 1.

By referring to the drawing and Figure 1 in particular it will be seen that the furnace regulator comprises a base plate 1 which is in turn bolted to a channel bracket 2. This channel bracket 2 is shown attached to a furnace casing 3 by means of metal screws 4 so that a bi-metallic expansion unit comprising a copper tube 5 and a steel rod 6 of the regulator are positioned slightly above the dome of the furnace. The copper tube 5 is threaded at its inner end into a threaded opening in the base plate 1. The steel rod 6 being positioned within the copper tube 5 and provided with a pointed inner end, while its outer end is affixed to the outer end of the copper tube 5 (not shown). It will thus be obvious that any expansion of the copper tube 5 will be substantially greater than that of the steel rod 6 and result in a horizontal movement of the pointed inner end of the steel rod 6. The remainder of the regulator utilizes this movement as a means of controlling the draft and checks of a warm air furnace.

The furnace regulator shown and described herein has been adapted for installation on a warm air furnace adjacent to the smoke pipe thereof so that the control arm of the regulator is positioned directly above the check on the said smoke pipe and connected directly thereto by a suitable chain; another chain being connected to the control arm and led over one or more pulleys to the draft door of the furnace. Positioned on the base plate 1 a slotted supporting bracket 7

serves to support a bar 8 by means of a pin 9 passed therethru; the supporting bracket 7 being positioned slightly above the pointed inner end of the steel rod 6 and the bar 8 positioned adjacent to this pointed inner end of the said steel rod 6. A slot 10 in the lower portion of the bar 8 is adapted to engage a pin 11 positioned between the upright ends of a pair of L-shaped control arms 12. These control arms 12 being pivoted to a pivot bracket 13 which is in turn attached in any suitable manner to the base plate 1. Positioned between the horizontal portions of the said L-shaped control arms 12, there is a control arm 14 which is pivoted to the said L-shaped control arms 12 by means of a pivot pin 15. In order that this control arm 14 will normally tend to remain in horizontal position, as shown in solid lines in Figure 1; a pair of springs 16 are provided which lead from an opening 17 in the inner most end of the control arm 14 to arms 18 of a bracket 19 positioned between the said pair of L-shaped control arms 12.

In order that the action of the control arm 14 be accelerated when the same moves in response to the movement of the steel rod 6, a pair of lever arms 20 are provided which are pivoted to and spring tensioned by means of spring incorporating brackets 21 (see Figure 3) adjustably positioned on the base plate 1. The outer ends of these lever arms 20 are provided with shoes 22 which are pivoted thereto and are adapted to slidably engage the inner end of the control arm 14. By referring to Figure 1 it will be seen that the control arm 14 is provided with a pair of lugs 23 near the pivot pin 15, which will, when the control arm 14 moves, serve to limit the sliding action of the lever arms 20 on the control arm 14. When this occurs the lever arm 20 reaching the lug 23 serves to force the control arm 14 into the position indicated by dotted lines in Figure 1.

It is obvious that the action shown in Figure 1 is that taking place when the furnace cools and the pointed inner end of the steel rod 6 moves inwardly against the bar 8 which in turn moves the control arm 14 thru the pair of L-shaped control arms 12; it being understood that the reverse action takes place when the furnace heats and the control arm 14 moves upwardly. It will also be seen that there is available a few degrees of normal movement of the control arm 14 during which time the shoes 22 on the lever arms 20 slide upon the inner end of the control arm 14; it being only at such time as one of the shoes 20 reaches the lug 23 that the lever action takes place and thus accelerates the motion of the control arm 14. In a practical installation of this regulator an eyelet 24 at the extreme outer end of the control arm 14 is preferably connected directly by means of a chain to the check on the smoke pipe of the furnace although it is obvious that if it is desirable to locate the regulator at the front of the furnace, the motion of the control arm may be applied to the draft door of the furnace by passing a connection chain from the eyelet 24 over a pulley so as to reverse the motion of the control arm in relation to the draft door.

In order that the regulator be adjustable to match varying heating conditions, a threaded rod 25 is passed thru a threaded opening in the supporting bracket 7 and has its inner end 26 positioned directly against the bar 8. The outer end of this threaded rod 25 extends outwardly thru a suitable housing 27 and has a suitable control wheel 28 incorporating a marker 29 po-

sitioned thereon. A relatively stiff coil spring 30 is positioned between the base plate 1 and the extreme upper end of the bar 8 and serves to overcome looseness in the pivot joints of the device and to maintain the various portions thereof in operating contact with one another and the actuating steel rod 6.

What I claim is:

1. A thermostatic control for warm air furnaces comprising a base plate adapted for mounting on a warm air furnace, a bi-metallic expansion unit mounted on said base plate and positioned so as to extend inwardly over the dome of the said furnace, means for effectively utilizing the motion caused by the said bi-metallic expansion unit, said means comprising a bracket mounted on the said base plate, a bar adjustably positioned in the said bracket and adjacent to the said bi-metallic expansion unit, a spring positioned between an upper end of said bar and said base plate, a pair of L-shaped control arms pivoted to the said base plate and adapted to function with the said bar, a control arm pivoted between the outer ends of the said pair of L-shaped control arms, a pair of lugs formed on said control arms, a pair of lever arms adjustably pivoted to the said base plate their outer ends adapted to slidably engage an inner end of the said control arm and thereby limited in their sliding action by said lugs so that the movement of the L-shaped control arms will result in a leverage action against the said control arm when the said lever arms reach the said lugs.

2. A thermostatic control for warm air furnaces comprising a bi-metallic expansion unit and means for effectively utilizing and controlling the motion caused thereby, said means comprising a base plate to which the said expansion unit is attached, a slotted supporting bracket positioned on the said base plate and adapted to carry a bar on a pin passed therethru, a spring positioned between an upper end of said bar and said base plate, a pair of L-shaped control arms pivoted to a bracket positioned on the said base plate, the upturned ends of the said L-shaped control arms provided with a pin adapted to engage a slot in the said bar, a control arm pivoted to the outermost ends of the said L-shaped control arms so that the majority of its length extends beyond the outermost ends of the said control arms and its innermost end is normally positioned between the said pair of L-shaped control arms by spring tension means, a pair of lugs formed on said control arm, lever arms adjustably pivoted to the said base plate and provided with shoes adapted to slidably engage the inner end of the said control arm, and thereby limited in their sliding action by the said lugs in such manner as to effectively apply leverage to the said control arm at such times as the said pair of L-shaped control arms are moved, the said leverage serving to effectively move the said control arm in relation to the said pair of L-shaped control arms.

3. A thermostatic control for warm air furnaces comprising a bi-metallic expansion unit and means for effectively utilizing and controlling the motion caused thereby, said means comprising a base plate to which the said expansion unit is attached, a slotted supporting bracket positioned on the said base plate and adapted to carry a bar on a pin passed therethru, a spring positioned between an upper end of said bar and said base plate, a threaded opening in the said slotted bracket thru which a threaded rod is

- passed so that it bears against the said bar, a control wheel affixed to the said threaded rod so that the same may be rotated and will effectively move the said bar in relation to the said expansion unit, a pair of L-shaped control arms pivoted to a bracket positioned on the said base plate, the upturned ends of the said L-shaped control arms provided with a pin adapted to engage a slot in the said bar, a control arm pivoted to the outermost ends of the said L-shaped control arms so that the majority of its length extends beyond the outermost ends of the said control arms and its innermost end is normally positioned between the said pair of control arms by spring tension means, a pair of lugs formed on the said control arm, lever arms adjustably pivoted to the said base plate and provided with shoes adapted to slidably engage the inner end of the said control arm in such manner as to effectively apply leverage of one of the lever arms thereto when the lever arm engages one of the said lugs at such times as the said pair of L-shaped control arms are moved the said leverage serving to effectively move the said control arm in relation to the said pair of L-shaped control arms after the said L-shaped arms and control arm have moved together in their limited range and one of the lever arms has reached one of the lugs on the control arm.
4. A thermostatic control for warm air furnaces comprising a channel section attached to the said furnace, a base plate bolted to the said channel section and carrying an expansion unit adapted to extend within the furnace casing and over the dome of the furnace, the said expansion unit comprising a copper pipe threaded into the said base plate and a steel rod attached to the said copper tube at their outermost ends, a slotted bracket positioned on the said base plate immediately above the inner end of the said steel rod, a bar suspended from the said slotted bracket in front of the said steel rod by means of a pin passed therethru and functioning in the said slot, a threaded rod positioned in a threaded opening in the said slotted bracket and provided with a control wheel and adapted to have its inner end engage the said bar adjacent to the said pin, a coil spring positioned between the upper end of the said bar and the said base plate to effectively hold the said bar in contact with the said steel rod, a pivot bracket attached to the said base plate, a pair of L-shaped arms pivoted therein, the upturned ends of the said L-shaped arms carrying a pin adapted to engage a slot in the said bar, a control arm pivoted between the outermost ends of the said L-shaped arms so that the majority of its length extends beyond the said ends of the L-shaped arms, a pair of lugs formed on the said control arm, a pair of lever arms adjustably pivoted to the said base plate having shoes formed on their outer ends adapted to slidably engage an inner end of the said control arm, and thereby limited in their sliding action by the said lugs in such manner that movement of the said L-shaped arms will result in one of the said shoes engaging one of the said lugs and by leverage move the said control arm in relation to the L-shaped arms, spring tension means connecting the innermost end of the said control arm with a bracket positioned between the said L-shaped arms so as to tend to maintain the control arm in horizontal relation with the said L-shaped arms.

CHARLES A. HARPMAN.
